UNITED STATES PATENT OFFICE.

WALTER F. TROTTER, OF CINCINNATI, OHIO, ASSIGNOR TO DETROIT STOKER COMPANY, OF DETROIT, MICHIGAN, A CORPORATION OF MICHIGAN.

UNDERFEED STOKER.

Application filed December 19, 1921. Serial No. 523,251.

This invention relates to underfeed stokers of that type in which the green fuel is fed longitudinally of a trough beneath the burning fuel and is gradually elevated into the zone of combustion. The invention consists primarily in various structural features of the furnace bed plates and the tuyère blocks and in a novel relation between said plates and blocks.

10 In the drawings:—

Figure 1 is a plan view of the improved stoker;

Figure 2 is a cross section view of the same taken on line 2—2 of Figure 1;

15 Figure 3 is a vertical sectional detail on line 3—3 of Figure 1 showing one of the rear end tuyère blocks;

Figure 4 is a perspective detail of one of the bed plates;

20 Figure 5 is a perspective detail of an inverted tuyère block;

Figure 6 is a cross section view of the same;

25 Figure 7 is a fragmentary plan view of the front tuyère block and a portion of the retort, supporting said block;

Figure 8 is a rear elevation view of said block with certain parts in section;

30 Figure 9 is a view of said block and associated structure in cross section;

Figure 10 is a fragmentary longitudinal sectional view of the stoker.

In these views the reference characters 1 and 2 respectively designate the front and 35 rear walls of a furnace and 3 a trough shaped retort into which the green fuel is fed and which passes through and extends rearwardly from the front wall of the furnace. 4 is a push rod operating within said 40 retort to assist feeding of the fuel. Upon each edge of said retort there rest the upper ends of a row of closely adjoining inclined bed plates 5, the lower ends of each row being supported in common upon a sill 6 formed by a beam 6. Said beam is flanged as indicated at 6^a and the bed plates 5 are formed with integral depending hooks 6^b engaging the flanges 6^a. Upon the upper end portion of each plate 5 there is mounted 45 one or more detachable tuyère blocks 7. Said blocks are each formed with a pair of holding lugs 8, downwardly projecting into openings 9 formed in the horizontal upper end portions of the bed plates. A 50 rod 10 forms a common means for securing

all the aligned tuyère blocks to the corresponding bed plates and for securing said bed plates to one another, said rod being passed through registering apertures in the lugs 8 and in ribs 10^a depending from the 55 plates 5. The rods 10 project slidably through the front wall 1 of the furnace so as to be readily accessible. By withdrawing said rods to a greater or less extent any of the tuyère blocks or bed plates can be removed from its position of use. The inclined top surface of each plate 5 is transversely shouldered as indicated at 11 at a suitable intermediate point preferably relatively near the tuyère blocks. The inclined 60 top faces of said plates 5 are ribbed as indicated at 12 to form shallow pockets 12^a both above and below the shoulder 11. Said pockets serve to retain a layer of fine 65 ash which acts as a heat insulation to protect the plates from the intense heat given out by the mass of fuel supported by said plates. Recesses 13 formed in the tops of the tuyère blocks serve a similar purpose. 70 14 designates dump plates, a row of which is arranged at each side of the furnace bed. Each row of plates 14 is mounted fast upon a rock shaft 15 extending through the front wall of the furnace and adapted to swing 75 said plates down when desired to permit the plates to discharge their load into the ash pits 15^a. 16 is an air chamber formed beneath the plates 5 and about the retort 3, air under pressure being delivered to said 80 chamber from any suitable source, as is common practice. Each of the tuyère blocks 7 is formed with an air passage 17 having an inlet in the bottom of said block communicating with the chamber 16. 85 As shown the majority of the blocks 7 have one side wall thereof formed with a plurality of air outlets 18 for discharging air above the retort, while each opposite side wall is provided with a single outlet 18^a for discharging air in the direction of inclination 90 of the plates 5. The number of air outlets may be varied in different blocks according to the fuel conditions normally prevailing adjacent said blocks. It is preferred to form the blocks 7 with internal ribs 95 19 just below the outlets 18 and 18^a as a preventive against ashes entering the tuyère blocks through said outlets and also to assist in giving discharging air a strictly lateral 100 direction. Preferably the ribs are turned 105 110

slightly upward at their free edges as is best seen in Figure 6.

21 designates a tuyère block of special form which is set into the front wall 1 of the furnace, said block bridging the retort 3 and being formed with legs 22 respectively seating upon the edges of said retort as is best seen in Figure 8. Said legs are terminally formed with lugs 23 which fit 10 into grooves 24 in the edges of the retort to assist in properly positioning the tuyère block. Also a lug 24^a projects forwardly from the block 21, engaging normally in a slotted keeper 24^b integrally upstanding 15 upon the inverted channel shaped plate 24^c which bridges the retort beneath the front wall 1. The lugs 23 and 24^a assist in properly positioning the block 21, and the grooves 24 permit said blocks to be slid rearwardly 20 if it becomes necessary to remove said block from its normal location in the wall 1. The legs 22 are hollow, forming air passages 25 into which air may rise from the chamber 16 and be delivered to the hollow upper portion 25 of the block, from which the air may discharge rearwardly through a plurality of outlets 26 having a suitable elevation above the retort. The air thus discharging supports combustion of such gases as may be 30 given off by the fuel upon its initial introduction into the furnace, said gases rising in proximity to the front wall 1.

28 designates a pair of tuyère blocks arranged in proximity to the rear furnace wall 2, said blocks having portions aligned with the row of blocks 7, and having portions projecting toward each other and substantially abutting. The blocks 28 are preferably provided with L-shaped portions 28' 40 which seat partially upon the adjacent plates 5 and partially upon a flat rear end portion 30 of the retort. Said blocks are supplied with air from the chamber 16 both through openings 9 such as have been described and 45 through openings 31 forming in the retort extremity 30. 32 designates inclined faces of the blocks 28 which constitute an upward extension of the inclined rear end face 33 of the retort. 34 are air ports discharging 50 forwardly through the inclined faces 32.

In the operation of the described invention, the fuel gradually discharging from the retort 3 feeds laterally in each direction passing over the row of tuyère blocks 7 and 55 feeding down the incline of the bed plates 5. The mass of fuel is subjected to a sudden drop in passing from above the tuyère blocks to the relatively low inclined faces of the plates 5 and a similar drop occurs when the 60 shoulder 11 is encountered by the fuel, the effect being to break up the masses of fuel and secure a more thorough combustion thereof. If for any reason it becomes necessary to inspect or replace any of the bed 65 plates or tuyère blocks the described con-

struction permits a ready removal of such parts. The supply of air delivered to the fuel by the tuyère blocks may be quite accurately predetermined according to the normal condition of the fuel in various parts 70 of the furnace by varying the number of outlets in the tuyère blocks at different points. Thus it will be observed that the blocks 7 nearest adjacent the front wall 1 are blank as regards outlets opening above 75 the plates 5 and have each only one outlet discharging above the retort. The next adjacent blocks have each only one outlet discharging above the bed plates and two outlets discharging above the retort, while each 80 of the remaining blocks has two outlets discharging above the bed plates and four outlets discharging above the retort. The inclined faces 32 of the rear blocks 28 cooperate with the inclined rear end 33 of the retort in causing the fuel to rise from the retort. The upwardly projecting portions of 85 said blocks provide at the same time for a discharge of air into the mass of fuel adjacent the rear wall. 90

An advantageous feature of the described construction is the detachable seating of the tuyère blocks upon the bed plates. Thus, not only said blocks but the elements which provide seats for the blocks are independently removable, so that the expense involved in replacing any block or its seat forming plate is minimized. 95

While the construction illustrated and described is of the side dumping type it will 100 be readily understood that certain features of the invention are equally applicable to an end dumping construction.

What I claim as my invention is:—

1. In a furnace bed, an inclined plate 105 transversely shouldered intermediately of its upper and lower ends to effect a drop of fuel, feeding down the incline, for the purpose of breaking up said fuel, said plate having its top surface formed with pockets 110 above and below said shoulder to retain heat insulating material.

2. The combination with a furnace bed, comprising a row of inclined plates, of 115 tuyère blocks respectively surmounting the upper end portions of said plates and a common means for securing said blocks to said plates and said plates to each other.

3. The combination with a furnace bed, comprising a row of inclined plates, of 120 tuyère blocks respectively surmounting the upper end portions of said plates, and a pin extending exteriorly of the furnace, detachably securing said blocks upon said plates and said plates to each other.

4. The combination with a trough-shaped retort, and a wall at one end of said retort, of a tuyère block set into said wall, bridging the retort and having hollow legs seating 125 upon the edges of the retort and depending 130

lugs respectively formed on said legs, the edges of the retort having grooves engaged by said lugs elongated to permit removal of the tuyère block from the wall.

- 5 5. In a furnace bed, a series of bed plates, each bed plate having a horizontal portion and an inclined portion, the horizontal portion of each bed plate having an opening therein, tuyères mounted on the horizontal portions of said bed plates and having lugs engaging the openings therein, ribs depending from the bed plates, and a member engaging said ribs and lugs for securing all of said tuyères to the corresponding bed plates and for securing said bed plates to each other.

6. In a furnace bed, the combination with an elongated bed plate extending between the tuyère and dump plate of the furnace and having an inclined portion, a horizontal portion at the upper end of the inclined portion, and a transversely shouldered portion intermediate the inclined and horizontal portions, said horizontal portion having a vertical opening therein for the passage of air, of a hollow tuyère mounted on the horizontal portion of the bed plate having an air inlet opening at the bottom engaging with the opening in the bed plate and having an air outlet opening in the wall thereof above the transversely shouldered portion of the bed plate, and means for positioning said tuyère on said bed plate including a lug extending downwardly from a wall of the tuyère engaging a wall of the opening in the horizontal portion of the bed plate.

7. In a furnace, the combination with a wall thereof, of a trough-shaped retort having grooves at the opposite sides thereof, an inverted channel-shaped plate extending longitudinally of the retort beneath a portion of the wall aforesaid of the furnace, an apertured lug carried by the plate, an inverted substantially U-shaped hollow tuyère bridging the retort at one end of the plate, said tuyère having air inlet openings at the lower ends of the hollow leg portions thereof, and an air outlet opening in the intermediate horizontal portion thereof, the lower wall of the horizontal portion of said tuyère being in substantial alignment with the top of said channel-shaped plate, and means for positioning said tuyère including a lug projecting from the horizontal portion thereof engaging the apertured lug of the plate, and lugs projecting from the leg portions thereof engaging the grooves in the sides of the retort.

8. In a furnace, the combination with a wall thereof, of a trough-shaped retort, an

inverted channel-shaped plate extending longitudinally of the retort beneath a portion of the wall aforesaid of the furnace, an inverted substantially U-shaped hollow tuyère bridging the retort and overlying the plate at one end thereof, said tuyère having air inlet openings at the lower ends of the hollow leg portions thereof, and an air outlet opening in the intermediate horizontal portion thereof, the lower wall of the horizontal portion of said tuyère being in substantial alignment with the top of said channel-shaped plate, and means secured to the tuyère and engaging said plate for removably positioning said tuyère.

9. In a furnace bed, a hollow tuyère having an air inlet opening at the bottom thereof, and air outlet openings in certain of the side walls thereof, the top of said tuyère being entirely closed and having a substantially V-shaped depressed portion to retain heat insulating material, the sides of the V-shaped portion merging into the apertured sides of the tuyère at the upper edges of the openings, whereby the air will be directed and oppositely deflected by the V-shaped portion through the said openings.

10. In a furnace, the combination with a wall thereof, of a trough-shaped retort having its rear end upwardly inclined from the bottom to the top of the trough and having a horizontal shelf portion projecting rearwardly from said end abutting the wall aforesaid of said furnace, said shelf portion having a vertical opening for the passage of air, and a tuyère block having the rear wall thereof abutting the wall aforesaid of the furnace and resting upon the shelf portion of the retort, said block also having an inclined wall extending downwardly from the upper edges of the rear wall thereof and disposed in substantial alignment with the inclined rear end portion of said retort, the inclined wall of said tuyère being provided with an air outlet opening for discharging air longitudinally of the retort.

11. In a furnace bed, a hollow tuyère having an air inlet opening at the bottom thereof and air outlet openings in certain of the side walls thereof, the top of said tuyère being entirely closed and provided with an inwardly depressed portion adapted to retain heat-insulating material, means for supplying air interiorly of said tuyère through said inlet opening, said depressed portion adapted to deflect the air to the said air outlet openings.

In testimony whereof I affix my signature.

WALTER F. TROTTER.
